E. WEINHEIM

FORCED FEED CROSSER

Original Filed Sept. 23, 1921

UNITED STATES PATENT OFFICE.

EMIL WEINHEIM, OF NEW YORK, N. Y.

FORCED-FEED CROSSER.

Original application filed September 23, 1921, Serial No. 502,593. Divided and this application filed
March 26, 1924. Serial No. 701,948.

This invention relates to the manufacture of artificial fabrics more particularly of substitute leather.

The object of the invention is to make possible the application of very viscous converting dope upon and its incorporation with a fragile body fabric itself incapable of withstanding the abrasion of a doctor blade. A further object of the invention is to provide controllable means for the production of a sheet of such dope to be laid continuously upon a relatively moving body fabric. A still further object of the invention is to provide for the movement and manipulation of such a sheet of dope at its source in such a way that the relative motion or a part of the relative motion between the source of this dope and the body fabric upon which it is to be laid is in whole or in part in the source of the dope itself.

The above and further objects of the invention will better be understood by reference to the illustrative embodiment of my invention described in the following specification in connection with the accompanying drawings which form a part hereof. The claims are directed to this illustrative embodiment solely for purpose of illustration and not limitation. This application is a division of my co-pending application, day's docket 1060, substitute tooled leather and process for making same, Ser. No. 502,593, filed Sept. 23, 1921.

In the drawings, Fig. 1 is a diagrammatic representation of a preferred type of apparatus for practicing my invention, the same being shown for the most part in elevation;

Fig. 2 is a plan view of the apparatus shown in Fig. 1; and

Fig. 3 is an enlarged cross-section through the plane of section line III—III of Fig. 1.

In practicing my invention, I employ a body fabric A of any suitable character, preferably one having a firm, smooth top surface and a lower surface of considerable pile. The top surface 1 of this body fabric is preferably colored to embody the color of the background for the finished product. A roll 2 of this fabric is indicated in the diagram of Fig. 1 and should be threaded through any usual type of dope applying apparatus, such as that diagrammatically indicated and be wound up as a finished product on the reel 3, it being understood

that any and all usual treatments immediately before reeling may be employed. The roll 4 of lace curtain material B or any other material to be incorporated upon the body fabric A and itself too fragile to withstand the abrasion action of a doctor blade is threaded through the apparatus to overlie the body fabric B being supported from underneath by A and the one lying on the other. Rolls 7 and 7 for drying purposes are power driven as is all the rest of the apparatus to cause uniform longitudinal movement of the fabric in the direction of the arrows.

A suitable fluid dope c is employed to combine the two fabrics A and B. This dope may be a composition of oxidized oils thinned with a volatile solvent of the general character used in the oil-cloth industry, but for some purposes I prefer a dope consisting of a pyroxalin compound such as that described in any of my prior applications in this art. The pyroxalin compound is preferred on account of its greater tendency to shrink upon setting. In fact, any dope usual to the art may be employed in this apparatus even to the very viscous dopes usually employed in conjunction with a doctor blade for forcing them into the fabric.

In the preferred practice of my invention, however, I employ no doctor blade but apparatus such as that illustrated diagrammatically in the figures. In this apparatus, the dope, which may be any of the dopes previously mentioned, is caused to flow downwardly upon the moving fabrics A and B from a hollow dope bar or closed trough C. This dope bar has an adjustable orifice 10, delivering the dope in a sheet directed substantially vertically downwardly and means is provided for regulating the width of this orifice such as the closure bar 30 adjustable by means of the adjustable bolts 31. By this means, the thickness of the sheet of dope, being extruded from the hollow bar C, may be regulated. The hollow dope bar C is of a length approximating the width of the fabric to be coated, although this exact length is not essential. It is arranged so that its orifice is lengthwise of the fabric to be coated and lengthwise of the travel of the fabric. It is guided and supported for transverse movement upon parallel ways 11 and 12 overlying the fabric. These ways are parallel to the plane of the

fabric. A dope reservoir D contains a maximum charge of dope and is connected with the movable trough C by a flexible metal conduit 13. Pressure is applied to the 5 interior of the container D through pressure pipe 14. Air pressure is satisfactory and this pressure is imparted through the duct 13 to the interior of the dope bar C. All of this hollow apparatus is designed to 10 withstand internal pressure.

The entire dope bar C is preferably reciprocated back and forth along the ways 11 and 12 at such variable rate of speed that the lay or lap applied transversely to 15 the body fabric shall be of uniform thickness.

In the embodiment illustrated, a cylinder 16, supplied with steam from the conduit 17, is controlled by an automatic valve 18 20 of usual construction in reciprocating steam engines and operates the piston rod 19 through a piston of usual construction. The reciprocation of piston rod 19, which is connected to the hollow dope bar C 25 imparts to it the desired movement. With the body fabric travelling in the direction of the arrow and the relative speeds adjusted properly, two laminations of dope sheet are progressively laid upon the moving body 30 fabric. This dope then passes through the interstices of the fabric B and incorporates itself with the body fabric A, binding the two together.

The body fabric A with its appliqué B 35 may be carried along through the apparatus in any suitable manner over guide rollers 20, 21 and 22, but it should be understood that, although both top and bottom rollers may be employed, the pressure between such rollers should be insufficient to 40 imbed the appliqué B in the body fabric A, as it is desired that the finished product have a decided raised effect when the lace curtain material is employed. This is not 45 true, however, for all appliqués B, nor is it a limitation for the broad use of this forced feed application of a sheet of dope.

In the operation of this movable dope bar, the first stroke of the piston rod 19 50 causes the application of a dope layer 32 in the form of a rhombus. The reverse stroke causes the application of another rhombus-shaped layer 33, a triangular half of which second rhombus covers a similar triangular 55 half of the first rhombus, and so on. It is in this way that the two layers or laminations of dope sheet are applied continuously upon the travelling strip beneath. It is thus 60 that something like a grain of relatively crosswise diagonal direction between the different layers is accomplished for the incorporated dope. One traverse through apparatus of this type is sufficient to fill in

all the interstices and form a complete bridge for the appliqué so that upon merging from the machine the product is complete and finished. 65

Another special advantage of the present process and apparatus is that the actual application of the sheet of dope is free from 70 anything except a sheet of dope contacting with the fabric to which the dope is applied. It should be understood that the usual drying apparatus for the fabric may be employed, the same to be located at any 75 convenient stage in the process and after the application of the dope sheet.

The inventive thought may have a variety of expressions as is contemplated in what I claim and desire to secure by United States 80 Letters Patent as follows:

1. In the manufacture of substitute leather, the method of applying dope comprising drawing along in a substantially horizontal plane a strip of fabric at a pre-determined rate of speed; discharging surface treating dope above said moving fabric in a substantially vertical sheet, the plane of which is lengthwise of the direction of movement of said body fabric; and causing said discharging sheet of dope to be moved back and forth transversely of 90 said moving strip of fabric at a predetermined rate to form diagonal overlapping 95 lays upon said strip of fabric. 95

2. An apparatus for applying dope to body fabric; a hollow dope bar; a flexible connection for supplying dope to said dope bar; means for causing a fabric to be coated to travel under said dope bar substantially 100 in the direction of its length; and means for reciprocating said dope bar transversely of said fabric.

3. In the manufacture of substitute leather, the process of applying dope to a body fabric comprising imparting continuous motion to the body fabric in a horizontal plane; extruding dope directly upon the moving body fabric and simultaneously imparting to the source of said extruding a movement having a component transverse to the direction of travel of said body fabric. 105

4. In apparatus for applying dope to a body fabric, a hollow dope bar; a pressure reservoir containing a maximum charge of dope; a duct between said dope bar and said reservoir and means for applying fluid pressure to said reservoir; means for drawing a fabric to be coated lengthwise of said dope bar; and means for reciprocating said dope bar transversely of the travel of said fabric. 115

In witness whereof, I have signed my name to this specification, this 10th day of November, 1923.

EMIL WEINHEIM.
